UNITED STATES PATENT OFFICE.

WILLIAM A. SINSEL, OF WAUKESHA, WISCONSIN.

WINDOW-SASH.

SPECIFICATION forming part of Letters Patent No. 293,099, dated February 5, 1884.

Application filed July 17, 1883. (No model.)

To all whom it may concern:

Be it known that I, WILLIAM A. SINSEL, of Waukesha, in the county of Waukesha and State of Wisconsin, have invented certain new and useful Improvements in Window-Sashes, of which the following is a full, clear, and exact description.

This invention relates to certain improvements in window-sashes, in which in one instance is employed a detachable cord socket-plate having at its lower end a knot-socket and at its upper end lips that fit under a recessed lock-plate, and in which in another instance is employed a removable section, to 15 which the sash-cord is fastened by nails or analogous means, said section being secured in place by keys, whereby the sash may be removed from the window-easing without removing the window-stop; and the invention 20 consists in the construction, arrangement, and combination of parts, all as hereinafter described and claimed.

Reference is to be had to the accompanying drawings, forming a part of this specification, 25 in which similar letters of reference indicate corresponding parts in all the figures.

Figure 1 is a front view, with parts broken away, of a window-sash made in accordance with my invention. Fig. 2 is a sectional plan 30 view of the same, taken on the line $x-x$ of Fig. 1; and Fig. 3 is a perspective view, on an enlarged scale, of one of the rope-fasteners, showing the main parts thereof separated from each other.

35 A represents the movable section, which, when in place, forms a part of the side pieces, b , of the sash B. The section A may be attached to the side piece, b , in various ways; but I prefer to attach it by means of a tongue-and-groove joint or by means of a dovetailed joint, as shown at d , thus adapting the section A to be slid longitudinally off from the edge of the side b .

40 C is the rope-fastener, attached to section A, for holding the outer end of the weight-rope f ; and D is the removable rope-fastener attached to the opposite side piece, b' , of the sash B, for holding the outer end of the weight-rope f' .

45 The fastener C is composed of the main casting c and the removable cap-plate c' , and is

held in place in the channel a of the sliding section A by the screw a' . The cap-plate c' and main casting c are formed upon the inside with the ribs e , and the cap-plate c' is 55 formed also upon the inside with the spur e' , and is held in place upon the main casting c by the screw a' , and lip j , formed at its upper end, which fits under the bridge c^2 of the main casting c and fulcrums the plate c' , so that 60 when screwed down by a screw, a^2 , the plate will clamp the rope between it and the main casting and cause the spur e^2 and ribs e to be embedded in the rope, and thus hold the rope with great firmness. 65

The rope-fastener D is composed of the cap-plate k and main casting d' , which are made in all respects like the parts c , c' of the fastener C, except that the main casting d' is extended upward, as shown at d^2 , to the top of the sash, 70 where it is bent, as shown at g , and formed with the downwardly-projecting spur h , that is adapted to be embedded in the upper end of the sash, the lower end of the casting being adapted to be held down in the groove b^2 , 75 of the side piece, b' , against the action of the weight on rope f' by the removable pin E, that passes through the side piece, b' , of the sash and through the lower end of the casting d' , as shown in Fig. 1. The cap-plate k 80 is formed with lip j' , spur f^2 , and ribs i' the same as in the fastener C, and the casting d' is formed with the ribs h' , and the cap-plate k is held in place by the lip j' , passing under the bridge k' , and by the screw a' , the same as in 85 the fastener C.

F is a removable pin that passes through side piece, b , of the sash B, and also through sliding section A, for holding said section down in place upon the edge of the side piece, 90 b , against the action of weight on rope f .

In order to remove the sash from the window-frame it is only necessary to withdraw the pins E F, whereupon the weights of the window attached to cords f , f' will lift upward 95 the removable rope-fastener D and sliding section A, leaving the sash B free to be taken out of the window-frame.

I do not abandon or dedicate to the public any patentable feature set forth herein and 100 not hereinafter claimed, but reserve the right to claim the same either in a reissue of any

patent that may be granted upon this application or in other applications for Letters Patent that I may make.

Having thus described my invention, I claim
5 as new and desire to secure by Letters Patent—

1. The removable section A of the window-sash B, provided with the rope-fastener C, substantially as and for the purposes set forth.
2. The sash B, having removable section A,
10 with rope-fastener C attached, in combination

with the removable rope-fastener D, substantially as and for the purposes set forth.

3. The removable section A, provided with rope-fastener C, and held in place by the removable pin F, substantially as described.

WILLIAM A. SINSEL.
